(57) **CLAIM**

The ornamental design for a cartoon cat straw cover, as shown and described.

DESCRIPTION

FIG. 1 is a perspective view of a cartoon cat straw cover showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The faded-out surfaces within the broken lines form no part of the claimed design. The broken lines represent the boundaries of the claim and form no part thereof.

1 Claim, 8 Drawing Sheets
